UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET COLLECTING AND ASSOCIATING MECHANISM.

1,325,974.

Specification of Letters Patent. Patented Dec. 23, 1919.

Application filed May 21, 1918. Serial No. 235,831.

To all whom it may concern:

Be it known that I, HOWARD M. BARBER, a citizen of the United States, and resident of Stonington, in the county of New London 5 and State of Connecticut, have invented a new and useful Improvement in Sheet Collecting and Associating Mechanism, of which the following is a specification.

In sheet collecting and associating mechanism it is very difficult to hold the sheets in register on the collecting cylinder as the grippers open to collect the sheets and open to transfer the sheets. This is especially true where a number of sheets are to be collected and associated and transferred and where the sheets are heavy.

The object of my invention is to provide novel means for insuring the proper holding of the sheets on the cylinder against slipping out of register while being collected, associated and transferred, said means including a rotary carrier having end and side grippers which coöperate to collect a number of sheets fed from one source, such, for 25 instance, as a source of main web sheet supply, and to combine therewith extra sheets fed from different sources, such for instance, as cover sheets, fed from one source and insert sheets fed from another source; the side 30 grippers serving to hold the sheets which are on the cylinder in register when the end grippers are opened to collect the main web sheets and to associate therewith the insert sheets and to transfer the associated and collected cover, main web and insert sheets to a 35 transfer cylinder. The side grippers open beyond the sides of the sheets as the grippers pass the collection, insert association and transfer points so as not to interfere 40 with the passage of the sheets.

A practical embodiment of my invention is represented in the accompanying drawings in which,

Figure 1 is a view in front elevation of so 45 much of a sheet handling machine as includes my invention.

Fig. 2 is a section taken in the plane of the line II—II of Fig. 1.

Fig. 3 is a section taken in the plane of 50 the line III—III of Fig. 1.

Fig. 4 is a section taken in the plane of the line IV—IV of Fig. 1, and

Fig. 5 is a detail section showing one of 55 the side grippers and one of its operating cams.

One or more webs pass over the web feed roll 1 and downwardly through the pair of coacting cutters 2, 3, and guides 4, 5, to one of the two sets of grippers 6 of the main web sheet feeding cylinder 7. The combined collecting and associating cylinder 8 may have one or more sets of end grippers 9 and one or more corresponding sets of side grippers 10. In the present instance, I have shown the cylinder 8 as having five sets of end 60 grippers and five sets of side grippers, the side grippers being located a considerable distance back of their end grippers so as to engage the sheets at about midway their length.

The cylinder 11 is an extra sheet feeding cylinder arranged to feed one or more extra sheets to each of the collecting and associating surfaces of the cylinder 8. In the present instance, this cylinder 11 is arranged to 65 feed cover sheets to the cylinder 8 at the proper intervals to be associated thereon with the collected main web sheets as will hereinafter appear.

The cylinder 11 is provided with a set of 70 end grippers 12 arranged to take the covers from a suitable feed table 13 and transfer them to the end grippers 9 of the combined sheet collecting and associating cylinder 8. The cylinder 14 is another extra sheet feeding cylinder arranged to feed one or more extra sheets to each of the collecting and associating surfaces of the cylinder 8. In the present instance this cylinder 14 is arranged to feed insert sheets to the cylinder 8 75 at the proper intervals to be associated with the associated cover sheet and collected group of main web sheets thereon as will hereinafter appear. The cylinder 14 is provided with a set of end grippers 15 arranged 80 to take the inserts from a suitable feed table 16 and transfer them to the end grippers 9 of the combined collecting and associating cylinder 8. 90

The cylinder 17 has a set of end grippers 100 18 arranged to take each group of collected and associated main web, cover and insert sheets from the end grippers 9 of the combined collecting and associating cylinder 8, at the proper times and transfer the so collected and associated sheets to a suitable 105 folding mechanism, 37, 38.

With the arrangement of the parts as herein illustrated, the combined collecting and associating cylinder 8 makes four-fifths 110

of a revolution for each revolution of the cover feeding cylinder 11, the insert feeding cylinder 14 and the transfer cylinder 17. The main web sheet feeding cylinder 7 makes two revolutions for each revolution of the cylinders 11, 14 and 17 and two and one-half revolutions for each revolution of the cylinder 8. The grippers 12 of the cover feeding cylinder 11 are tumbler operated and are closed to take the cover sheets from the table 13 every revolution of the cylinder 11, by the coaction of the tumbler cam 19 with the tumbler pin 20. The grippers 12 are opened to transfer their cover sheet to the end grippers 9 of the cylinder 8, every revolution of the cylinder 11, by the coaction of the tumbler cam 19 with the tumbler pin 21.

The grippers 15 of the insert feeding cylinder 14 are tumbler operated and are closed to take the insert sheet from the table 16 every revolution of their cylinder 14, by the coaction of the tumbler cam 22 with the tumbler pin 23. The grippers 15 are opened to transfer their insert sheet to the end grippers 9 of the cylinder 8, every revolution of the cylinder 14, by the coaction of the tumbler cam 22, with the tumbler pin 24.

The grippers 18 of the transfer cylinder 17 are operated every revolution of the cylinder 17, by the fixed cam 25, to engage and grip the collected and associated main web, cover and insert sheets every one and one-fifth revolutions of the combined collecting and associating cylinder 8.

A fixed cam 26 controls the operation of the grippers 6 on the main web sheet feeding cylinder 7, to take the sheets from the guides 5, 4, and transfer them to their respective end grippers 9 on the cylinder 8. A fixed cam 27 is arranged in position to successively control the operation of the end grippers 9 to take the main web sheets from the feeding cylinder 7. A movable cam 28 is moved in position every revolution of the cover feeding cylinder 11, by a rotary cam 29 to open a set of end grippers 9 to receive the cover sheet. A movable cam 30 is moved into position every revolution of the insert feeding cylinder 14, by a rotary cam 31 to open a set of end grippers 9 to receive an insert sheet on top of a collected and associated group of main web and cover sheets. A movable cam 32 is moved into position every revolution of the transfer cylinder 17, by a rotary cam 33, to permit the transfer of the collected and associated group of main web, cover and insert sheets to the said transfer cylinder. The side grippers 10 are opened by the cams 34 as they pass the transfer point between the cylinders 7 and 8. They are again opened by the cams 35 as they pass the transfer point between the cylinders 14 and 8, and they are again opened by the cams 36 as they pass the trans-

fer point between the cylinders 8 and 17. These last named cams 36 are sufficiently long to keep the side grippers open as they pass the transfer point between the cylinders 11 and 8. It is to be understood that these side grippers are yieldingly held closed except when opened by the said sets of cams 34, 35, 36.

In the cycle of operations, a set of end grippers 9 on the cylinder which has just transferred a collected and associated group of main web, cover and insert sheets to the transfer cylinder 17, will first take a cover sheet from the cylinder 11; they will then collect thereon a group of main web sheets from the repeated coaction with the cylinder 7, and they will then take an insert sheet on top of the collected group of main web sheets. They will finally transfer this so collected and associated group of main web, cover and insert sheets to the transfer cylinder 17. During the repeated opening of this set of end grippers, their corresponding set of side grippers will close upon the sheets on the cylinder 8 and hold the sheets from slipping out of register, thus maintaining absolute control of the sheets at all times until they are transferred to the folding cylinder.

While I have disclosed my invention as applied to a five-way combined collecting and associating cylinder arranged to collect four main web sheets or groups of sheets and associate a cover insert sheet therewith, it is obvious that I do not wish to limit myself to this particular arrangement.

What I claim is:—

1. Sheet collecting and associating mechanism including a combined collecting and associating cylinder having end and side grippers coöperating to collect a number of sheets and combine therewith extra sheets fed from different sources.

2. Sheet collecting and associating mechanism including a combined collecting and associating cylinder having end and side grippers coöperating to collect a number of main web sheets and combine therewith cover and insert sheets.

3. Sheet collecting and associating mechanism including a combined collecting and associating cylinder having end and side grippers coöperating to collect a number of main web sheets and combine therewith cover and insert sheets fed from different sources.

4. Sheet collecting and associating mechanism including a combined collecting and associating cylinder having end and side grippers coöperating to collect a number of sheets, combine therewith extra sheets fed from different sources and to transfer the so collected and associated sheets.

5. Sheet collecting and associating mechanism including a combined collecting and associating cylinder having end and side gri-

115

120

125

130

pers coöperating to collect a number of main web sheets, combine therewith cover and insert sheets and to transfer the so collected and associated sheets.

5 6. Sheet collecting and associating mechanism including a combined collecting and associating cylinder having end and side grippers coöperating to collect a number of main web sheets, combine therewith cover 10 and insert sheets fed from different sources and to transfer the so collected and associated sheets.

7. Sheet collecting and associating mechanism including a combined collecting and 15 associating cylinder having end and side grippers coöperating to collect a number of sheets and combine therewith extra sheets fed from different sources, the side grippers serving to close on and hold the sheets which 20 are on the cylinder as the end grippers are opened to receive additional sheets.

8. Sheet collecting and associating mechanism including a combined collecting and associating cylinder having end and side 25 grippers coöperating to collect a number of main web sheets and combine therewith cover and insert sheets, the side grippers serving to close on and hold the sheets which are on the cylinder as the end grippers 30 are opened to receive additional sheets.

9. Sheet collecting and associating mechanism including a combined collecting and associating cylinder having end and side 35 grippers coöperating to collect a number of main web sheets and combine therewith cover and insert sheets fed from different sources, the side grippers serving to close on and hold the sheets which are on the cylinder as the end grippers 40 are opened to receive additional sheets.

10. Sheet collecting and associating mechanism including a combined collecting and associating cylinder having end and side grippers coöperating to collect a number of sheets and combine therewith extra sheets fed from different sources, the side grippers serving to close on and hold the sheets which are on the cylinder as the end grippers are opened to receive additional sheets and also 50 as the end grippers are opened to transfer the so collected and associated sheets.

11. Sheet collecting and associating mechanism including a combined collecting and associating cylinder having end and side 55 grippers coöperating to collect a number of main web sheets and combine therewith cover and insert sheets, the side grippers serving to close on and hold the sheets which are on the cylinder as the end grippers are 60 opened to receive additional sheets and also as the end grippers are opened to transfer the so collected and associated sheets.

12. Sheet collecting and associating mechanism including a combined collecting and 65 associating cylinder having end and side

grippers coöperating to collect a number of main web sheets and combine therewith cover and insert sheets fed from different sources, the side grippers serving to close on and hold the sheets which are on the cylinder as the end grippers are opened to receive additional sheets and also as the end grippers are opened to transfer the so collected and associated sheets.

13. Sheet collecting and associating mechanism including web sheet cutters and a combined collecting and associating cylinder having end grippers arranged to take extra sheets fed from different sources and to collect sheets fed from the cutters, and 80 side grippers arranged to hold the sheets which are on the cylinder as the end grippers are opened to collect.

14. Sheet collecting and associating mechanism including web sheet cutters and a combined collecting and associating cylinder having end grippers arranged to take extra sheets fed from different sources and to collect sheets fed from the cutters, and side grippers arranged to hold the sheets 90 which are on the cylinder as the end grippers are opened to collect.

15. Sheet collecting and associating mechanism including web sheet cutters and a combined collecting and associating cylinder having end grippers arranged to take a cover sheet fed from one source, collect thereon sheets fed from the cutters and to take an insert sheet fed from another source, and side grippers arranged to hold the 100 sheets which are on the cylinder as the end grippers are opened.

16. Sheet collecting and associating mechanism including web sheet cutters, a transfer cylinder and a combined collecting and associating cylinder having end grippers arranged to take extra sheets fed from different sources to collect the sheets fed from the cutters and to transfer the so collected and associated sheets to the transfer cylinder, and side grippers arranged to hold the sheets which are on the collecting and associating cylinder as the end grippers are 105 opened.

17. Sheet collecting and associating mechanism including web sheet cutters, a transfer cylinder and a combined collecting and associating cylinder having end grippers arranged to take a cover sheet from one source, to collect thereon sheets fed from the cutters, to take an insert sheet fed from another source and to transfer the so collected and associated sheets to the transfer cylinder, and the side grippers arranged to hold the sheets which are on the collecting and associating cylinder as the end grippers are 120 opened.

18. Sheet collecting and associating mechanism including a combined collecting and associating cylinder having coöperating end 130

- and side grippers arranged to alternately engage and hold successive sheets of a collection on the cylinder and to engage and hold extra sheets fed from different sources 5 to be combined with said collection.
19. Sheet collecting and associating mechanism including a combined collecting and associating cylinder having coöperating end and side grippers arranged to alternately engage and hold successive sheets of a collection on the cylinder, and to engage and hold cover and insert sheets to be combined with said collection. 10
20. Sheet collecting and associating mechanism including a combined collecting and associating cylinder having coöperating end and side grippers arranged to alternately engage and hold successive sheets of a collection on the cylinder, and to engage and hold 15 cover and insert sheets fed from different sources to be combined with said collection.
21. Sheet collecting and associating mechanism including web sheet cutters and a combined collecting and associating cylinder 20 having coöperating end and side grippers arranged to alternately engage and hold successive web sheets of a collection on the cylinder and to engage and hold extra sheets fed from different sources to be combined 25 with the said collection.
22. Sheet collecting and associating mechanism including web sheet cutters and a combined collecting and associating cylinder having coöperating end and side grippers arranged to alternately engage and hold successive web sheets of a collection on the cylinder and to engage and hold cover and insert sheets to be combined with the said collection. 30
23. Sheet collecting and associating mechanism including web sheet cutters and a combined collecting and associating cylinder having coöperating end and side grippers arranged to alternately engage and hold successive web sheets of a collection on the cylinder and to engage and hold cover and insert sheets fed from different sources to be combined with the said collection. 35
24. Sheet collecting and associating mechanism including web sheet cutters, a transfer cylinder, a combined collecting and associating cylinder having coöperating end and side grippers arranged to alternately engage and hold successive web sheets of a collection on the cylinder and to engage and hold extra sheets fed from different sources to be combined 40
- 5 to be combined with said collection, the side grippers serving to hold the so collected and associated sheets as the end grippers are opened to transfer the same to the transfer cylinder. 60
25. Sheet collecting and associating mechanism including web sheet cutters, a transfer cylinder and a combined collecting and associating cylinder having coöperating end and side grippers arranged to alternately engage and hold successive web sheets of a collection on the cylinder and to engage and hold cover and insert sheets to be combined with said collection, and the side grippers serving to hold the collected and associated sheets 65 as the end grippers are opened to transfer the same to the transfer cylinder. 70
26. Sheet collecting and associating mechanism including web sheet cutters, a transfer cylinder and a combined collecting and associating cylinder having coöperating end and side grippers arranged to alternately engage and hold successive web sheets of a collection on the cylinder and to engage and hold cover and insert sheets fed from different sources to be combined with said collection, the side grippers serving to hold the so collected and associated sheets as the end grippers are opened to transfer the same to the transfer cylinder. 75
27. Sheet collecting and associating mechanism including a combined collecting and associating cylinder having extra sheet taking points and a main web sheet collecting point, means for feeding sheets to said points and end and side grippers on the cylinder coöperating to take extra sheets and collect the main web sheets, the side grippers being arranged to hold the sheets which are on the cylinder as the end grippers are 80 opened. 85
28. Sheet collecting and associating mechanism including a combined collecting and associating cylinder having cover sheet and insert sheet taking points and a main web sheet collecting point, means for feeding the sheets to said points and end and side grippers on the cylinder coöperating to take a cover sheet, to collect the main web sheets thereon and to take an insert sheet, the side grippers being arranged to hold the sheets which are on the collecting cylinder as the end grippers are opened. 90
- In testimony that I claim the foregoing as my invention, I have signed my name this 110 seventeenth day of May, 1918.
- HOWARD M. BARBER.
